UNITED STATES PATENT OFFICE.

GEORGE P. TAYLOR, OF CLINTON, MASSACHUSETTS.

DESIGN FOR A SHEET.

SPECIFICATION forming part of Design No. 35,489, dated December 24, 1901.

Application filed November 23, 1901. Serial No. 83,486. Term of patent 14 years.

To all whom it may concern:

Be it known that I, GEORGE P. TAYLOR, a citizen of the United States, residing at Clinton, in the county of Worcester and State of Massachusetts, have invented and produced a new and original Design for a Sheet, of which the following is a specification, reference being had to the drawings forming a part thereof.

10 My invention relates to sheets for beds; and it consists in a new and original design for a sheet, as will be hereinafter fully described.

15 In my sheet there is a greater thickness or weight in the central portion and less thickness or weight on each side of the central portion. The thickness or weight in the central portion is substantially uniform, while in the side portions between the central portion and the selvages the thickness or weight is graduated from the central portion toward the selvages.

20 Referring to the drawings, Figure 1 is a plan view of a sheet, showing my design; and Fig. 2 is a cross-section through the sheet on line 22, Fig. 1.

25 In the accompanying drawings, A is a sheet for a bed, showing my design.

a a are hems at the top and bottom of the sheet, and b b are the finished or selvage edges 30 at the sides of the sheet.

In the sheet A all the transverse lines c, which extend in the direction of the width of the sheet and represent what are termed "filling" or "weft" threads, are of uniform size and at equal or uniform distances apart. The 35 lines d, which extend in the direction of the length of the sheet and represent what are termed "warp-threads," are so made and arranged as to make a greater thickness or weight in the central portion and less thickness or weight in the side portions between the central portion and the selvage edges.

The essential feature of my design is a greater thickness or weight in the central longitudinal portion of the sheet and less thickness or weight in the side longitudinal portions between the central portion and the selvage edges, the thickness or weight of the side longitudinal portions of the sheet being graduated from the central portion toward the 50 selvage edges.

What I claim is—

The design for a sheet, substantially as shown and described.

GEO. P. TAYLOR.
